UNITED STATES PATENT OFFICE.

ALVIN C. KENWORTHY, OF WALLA WALLA, WASHINGTON.

INTERNAL-COMBUSTION ENGINE.

Application filed November 13, 1919, Serial No. 337,752. Renewed July 19, 1922. Serial No. 576,143.

To all whom it may concern:

Be it known that I, ALVIN C. KENWORTHY, a citizen of the United States, residing at Walla Walla, in the county of 5 Walla Walla and State of Washington, have invented certain new and useful Improvements in Internal-Combustion Engines, of which the following is a specification.

This invention relates to improvements in 10 internal combustion engines of the two-cycle type and has for its object to provide improvements of this character in which one, two or three connecting rods may be used as required.

15 A further object is to provide an engine of this class which may be simply and efficiently cooled, either by air or water or other mediums.

20 A further object is to provide an engine relatively free of valves.

A further object is to provide an engine having a minimum of vibration.

With these and other objects in view the 25 invention consists in certain novel features of construction and combinations and arrangement of parts, as will be more fully hereinafter described, and that the invention may be better understood reference is had to the accompanying drawings, in which:—

30 Fig. 1 is a plan view of the internal combustion engine with part broken away;

Fig. 2 is a sectional elevation thereof;

Fig. 3 is a partial plan view showing my 35 preferred form of crank;

Fig. 4 is a partial sectional elevation showing my preferred form of exhaust outlet; and

Fig. 5 is a cross section through 5—5 of Fig. 4.

40 To give a clear understanding of the invention let it be understood that this engine is of the two-cycle type and that the principal is equally applicable to a two end cylinder engine as shown in the drawings or to

45 a single end cylinder engine, for the two end cylinder engine is merely a double single end cylinder engine, and in these specifications a single end cylinder only will be explained.

50 In the drawings like numerals refer to like parts throughout and 1 represents the engine frame which consists of the usual bed plate and supports which hold the stationary pistons 2. The stationary piston is ported 3, either as shown in Fig. 4 wherein the intake port only occurs, or as shown in

Fig. 2 wherein occurs both the intake port 3 and the exhaust port 4; the intake port communicates with the carburetor and is provided with a valve 5 to prevent a return 60 pressure reaching the carburetor (not shown). A second port 6 connects with the port 7 in the cylinder 8 and is offset to present the outlet orifice 9 out of register with the port 6 as the cylinder passes over the 65 stationary piston.

Where the exhaust port occurs in the stationary piston, as shown in Fig. 2, and as above mentioned, it is designed to register with the exhaust port 10 of the cylinder, and 70 is placed slightly in advance of the intake port as shown.

At diametrically opposite points in the stationary piston are slots 11 extending longitudinally thereof to provide a passage 75 through which a connection may be made between the plunger 12 and the cylinder 8. The head 13 of the piston is solid and is provided with a deflecting fin 14 to guide the explosive gas toward the forward end of the 80 cylinder thus to more efficiently purge the cylinder of the burnt gases.

The cylinder 8 consists of a head 15 and the above mentioned intake port 7 and the exhaust port 10 and (see Fig. 4) the exhaust 85 port works over the orifice 16 and forms a cut off valve therewith. The cylinder is provided with the usual spark plugs 17 which connect electrically with the terminals 18 which are adjustably mounted on the rod 19; and being adjustable the spark may readily be advanced or retarded as desired to suit the best running conditions.

Within the stationary piston 2 is the 90 above mentioned plunger 12 which is similar to the usual internal combustion engine piston with the wrist pin 20 however positioned at the open end of the plunger to register with the said slots at the lower end of the plunger travel.

100 The wrist pin extends laterally through the slots 11 and into the cylinder uniting co-operatively the plunger and the cylinder with the stationary piston positioned between the plunger and the cylinder with no 105 slidale contact between the two.

The wrist pin may be extended to receive connecting rods 21 which with the connecting rod 22 will require a three throw crank shaft 23, it is now obvious that either one 110 connecting rod 22 may be employed or two connecting rods 21, or three connecting rods

21 and 22 may be used depending upon the class of engine and the work required. My preferred form however is the centrally disposed connecting rod 22 as in this position 5 the rod and crank shaft may readily be enclosed.

Radiating vanes 24 may be used for cooling purposes or a water jacket not shown may surround the movable cylinder and attached to the stationary piston or the uprights of the engine frame.

The usual rings are provided on the stationary piston and the plunger.

In operation the gas is drawn into the 15 stationary piston through the port 3 by the movement of the reciprocating plunger 12 toward the open end. On the return of the plunger the valve 5 closes and the gas is compressed within the stationary cylinder 20 until the port 7 registers with the port 6 at which time the compressed gas rushes through these ports and striking against the deflector 14 is turned in its path toward the end of the cylinder which filling forces 25 the burned gases out at the exhaust ports 10 and 16 (or 4 as the case may be), the port 10 being advanced to give perfect purging to the cylinder. The cylinder is now filled 30 with gas and on the return stroke, making one complete revolution, the gas is compressed while the plunger is drawing in its second charge. With the gas compressed 35 the spark plug closes contact with the terminals and the resultant spark ignites the compressed gas when the cylinder is forced away from the stationary piston.

I thus provide an explosion at each revolution of the crank shaft; I also have a maximum of power during the compression 40 stroke overcoming the compression of the plunger; and compressing the gas in the cylinder, and drawing in the explosive charge, on the return stroke; thus providing 45 an engine of great efficiency.

With the design as shown in Figs. 1 and 45 2 respectively it will be noted that with the one double ended cylinder I provide an engine equivalent to a four cylinder, four-cycle type engine, and also, from the very 50 nature of its construction, reduce the vibration to the minimum.

Having thus described my invention, I claim:

1. In an internal combustion engine, the 55 combination of a ported, slotted, stationary piston, a cylinder on said stationary piston, a plunger within said stationary piston, a connecting rod, and a means for cooperatively uniting the said plunger and the 60 said cylinder through said slot, with the said connecting rod rotatably mounted on said means.

2. In an internal combustion engine, a 65 frame, a slotted stationary piston attached to said frame, a cylinder mounted on said

stationary piston, a plunger, a means for cooperatively joining the said cylinder and the said plunger through the slot in said piston, and a connecting rod joining said means with the crank shaft of said engine. 70

3. In an internal combustion engine, a frame, a stationary piston attached to said frame and provided with diametrically opposite slots, a ported cylinder mounted on said stationary piston, a plunger movable 75 cooperatively with said cylinder and out of slidable contact therewith, and a wrist pin cooperatively connecting the said cylinder and the said plunger through said slots and designed to rotatably mount a connecting rod.

4. In an internal combustion engine, a frame, a stationary piston attached to said frame and provided with diametrically opposite slots extending longitudinally thereof, a ported cylinder mounted and reciprocally operable on said stationary piston, a plunger mounted and reciprocally operable within said stationary piston, a wrist pin cooperatively connecting the said cylinder and the said plunger through said slots and designed to rotatably mount a connecting rod.

5. In an internal combustion engine, a frame, a ported hollow stationary piston rigidly attached to said frame, said piston being provided with diametrically opposite slots extending longitudinally thereof, a ported cylinder mounted and reciprocally operable on said stationary piston, a plunger mounted and reciprocally operable within said hollow stationary piston and movable cooperatively with said cylinder and out of slidable contact therewith, a means for cooperatively connecting said plunger and said cylinder through said slots, and a connecting rod rotatably mounted on said means.

6. In an internal combustion engine, a frame, a ported hollow stationary piston rigidly attached to said frame, said piston being provided with slots, in the sides thereof, and having a deflecting plate on the inner end thereof, a cylinder operably mounted on said piston and having an intake port and an exhaust port contained therein and controlled by the reciprocating movement of said cylinder, a plunger mounted within said hollow stationary piston and connected through the slots thereof with said cylinder, and a connecting rod connecting the said plunger with the crank shaft of the engine.

7. In an internal combustion engine, a frame, a stationary piston mounted on said frame, a cylinder having ports therein with one of said ports advanced and with both of said ports automatically controlled by the reciprocating movement of said cylinder, and mounted on said piston, a plunger with

in said piston, a wrist pin cooperatively connecting the said cylinder and the said plunger, and a connecting rod rotatably mounted on said wrist pin to connect with the crank shaft of said engine.

8. In an internal combustion engine, a frame, a plurality of slotted stationary pistons mounted on said frame, a ported two

end cylinder slidably mounted on said stationary pistons, plungers operating within the said pistons cooperatively with the said cylinder through said slots, and a connecting rod connecting said plunger with the crank shaft of said engine.

In testimony whereof I affix my signature. 15
ALVIN C. KENWORTHY.
